UNITED STATES PATENT OFFICE.

LOUIS A. GRAHAM, OF CHICAGO, ILLINOIS.

PERMUTATION ILLUMINATED SIGN.

Application filed March 3, 1922. Serial No. 540,928.

To all whom it may concern:

Be it known that I, LOUIS A. GRAHAM, a citizen of the United States, residing at Chicago, in the county of Cook and State 5 of Illinois, have invented certain new and useful Improvements in Permutation Illuminated Signs, of which the following is a specification.

This invention relates to a sign in which 10 the lines composing characters or devices desired to be expressed are produced of light spots, and particularly to a sign of this character in which the light spots are produced by apertures in a wall interposed in 15 the path of light from a source. It has been proposed to puncture such a wall on lines corresponding to characters to be expressed, and it has even been suggested to provide a metallic wall with weakened spots arranged 20 in various lines so that the openings could be selectively formed in the wall for the purpose stated.

Now, the primary object of the present invention is to provide a wall interposed into a 25 path of light which can not only be utilized for selectively developing light emitting apertures in lines corresponding to characters or devices to be expressed, but one which provides for permutation use in the sense 30 that continuity of opaqueness can be restored at will and new designs or outlines of light emitting spots selectively developed as frequently as desired; and, accordingly, an underlying feature of the invention consists in 35 constructing the light controlling wall with an area of closely related light releasing perforations, symmetrically distributed in the loci of lines constituent of various characters or devices to be expressed, and equipping 40 these perforations with light obstructing closures, replaceably as well as removably adapted individually to said apertures, so that after the light controlling wall has been manipulated to develop a sign composed of words, devices, or other matter of 45 expression and used for the desired length of time, it can be restored to its original complete opaqueness by the mere act of restoring displaced closures to the previously selected 50 apertures, and an entirely new sign can be developed by the selection and opening up of the apertures existing in a different set of lines.

Another object is to provide a construction 55 of closure plug that can be made cheaply

and with great accuracy and that can be introduced into apertures with ease and displaced therefrom when desired by continued movement in the same direction, but notwithstanding such ease of introduction 60 and expulsion will accurately retain its place in the aperture and will automatically enter into such intimate contact with the walls of the apertures as to thoroughly arrest 65 the light.

Accordingly, another feature of the invention consists in producing closure plugs longitudinally split for a portion of their length to render them radially resilient, and preferably hollow so that they will receive 70 and confine the instrument used for displacing them. These plugs are preferably formed by striking up sheet metal blanks of proper design.

Another object of the invention is to provide a suitable housing serving the combined purpose of mounting a light source and controlling the distribution of light uniformly to the area of the light screening wall; also preferably adapting the housing 80 to catch and collect plugs displaced in opening up apertures in composing a sign, and holding these displaced plugs within convenient reach for use in restoring them to the perforations; and, accordingly, other features of the invention consist in providing a housing with a source of light but having the light concealed from direct radiation toward the field of perforations, and delivered thereto only by reflection under 85 conditions which will render illumination of the entire field of perforations sufficiently near uniform to avoid serious contrast in the brilliancy of light spots produced in different portions of the field; this effect being produced preferably by locating the source of illumination in a pocket beyond the field of perforations, as, for instance, in a dome of the casing above such field, and having the light rays delivered from said 90 pocket or dome into the space behind the perforated field and against surfaces, for instance, enameled or otherwise whitened interior walls of the housing, which reflect the light toward the field.

Still another feature in the construction of the housing consists in adapting the latter to confine in its lower portion plugs that are displaced from the field of perforations.

Figures 1, 2, and 3 are, respectively, an 110

end elevation, a front elevation, and a top plan view of the preferred embodiment of the invention.

Figures 4, 5, and 6 are detail views illustrating the preferred construction of aperture closing plug; Figure 4 being a detail view on an enlarged scale of a portion of a perforated plate containing the new form of plug; Figure 5 being an end view of the plug; and Figure 6 showing a blank from which the plug may be made.

According to Figures 1 to 3, 1 represents a housing containing a light source 2, and 3 represents a wall introduced into the path 10 of light from said source, and having an area of closely related light-releasing perforations symmetrically distributed in the loci of lines constituent of various characters or devices to be expressed, and adapted 15 to contain light obstructing plugs 4 that constitute closures for said perforations that are not only readily displaceable to develop light emitting openings 4^a, but are conveniently replaceable in the perforations in 20 a manner to restore continuity of opaqueness of the light controlling wall, so that said wall is adapted to develop any desired character or device at will and repeatedly; or, in other words, so that the wall, when 25 related to a suitable source of light, becomes a permutation illuminated sign developed by transmitted light. Preferably, the bottom of the housing 1 serves as a pocket 5 to receive and confine displaced 30 plugs 4 from the wall 3; the meeting surfaces of the plugs and perforations being so fitted together preferably by making the plugs radially resilient, that the plugs can be displaced selectively by the use of a 35 suitable instrument when the wall is in its light controlling position; and the wall is 40 preferably mounted for movement, as, for instance, through the medium of hinge 6 (Fig. 1) to permit convenient recovery from receptacle 5 of displaced plugs that are to 45 be restored to the perforations.

There is preferably provided in front of the light controlling wall 3 a light modifying wall 7 of glass or other translucent material having a character appropriate to the modification of light to be effected, for instance, a colored glass or one having a prismatic or other irregular surface or surfaces to develop light refracting or diffusing 50 effects so as to merge the spot-like beams emitted through the perforations, and this light modifying wall is preferably carried in a frame 8 which is rendered removable from in front of the light controlling wall 3, as, for instance, by hinging it at 9.

The housing 1, carrying the perforated wall 3, is preferably provided with a dome 10 to receive the light source 2, and the latter comprises two lamps presented inwardly from the ends of the dome in posi-

tion to be screened from direct radiation of light toward the perforations 4^a, and the inner walls 11, 12, and 13 of the housing 1 are made into diffusing reflectors, as, for instance, by covering them with white 70 enamel or other white surfacing material.

As shown in Figures 4, 5 and 6, the plug is of such a nature that it can be both inserted from the front and displaced from the front, and when inserted can be pressed until it is flush with the outer surface of the plate, thereby avoiding projections on the front of the plate and affording the important advantage of permitting the letters or characters to be sketched upon the surface of the plate, for instance, with chalk or crayon as a preliminary to pushing out the light holes to define the same, and permitting the sign to be arranged, composed, spaced, etc., by sketching it upon the plate 80 as many times as may be necessary to outline it in satisfactory form before undertaking the labor of displacing the plugs. The surface of the plate will preferably be of a nature that will take the crayon or 90 chalk and permit it to be readily rubbed off when desired.

A plug that can be passed entirely through the plate by inserting it from the front and displacing it by pushing it the rest of the way through, may be provided in the form of small cylinders of wood, fiber, metal, or other material fitting snugly enough to make a friction hold, but it is preferred to produce a plug by shaping up sheet metal from a suitable blank, such, for instance, as that shown at 14 in Figure 6, to produce the plug 4 (Figures 4 and 5) with longitudinally slotted side walls that render the plug radially resilient, and thereby better adapt it to retain its position in and assume light arresting relation to the perforations of the wall. An advantage in making the plugs hollow is that they are adapted to receive and confine a 100 displacing instrument while they are being displaced from the wall as suggested in Figure 1.

I claim:

1. A permutation illuminated sign comprising a light controlling wall having an area of perforations disposed therein in the loci of lines constituent of characters or devices to be expressed by the sign, and light arresting plugs insertable in said perforations at will, the transverse dimension of the plugs throughout their length being not greater than that of the perforations, whereby the plugs are rendered displaceable therefrom by a continued movement 115 in the direction of insertion.

2. A permutation illuminated sign comprising a light controlling wall having an area of perforations symmetrically disposed therein in the loci of lines constituent 120

- of characters or devices to be expressed, and plugs displaceably and replaceably adapted to said perforations; the insertion of said plugs being in an inward direction, and displacement thereof being by a continued movement in the direction of insertion, and a receptacle on the inside of the wall adapted to receive plugs displaced from said wall.
3. A permutation illuminated sign comprising a housing having a perforated wall and an interior source of light; said wall having plugs insertable into its perforations by a movement from the outside to ward the inside and displaceable therefrom by continued movement toward the inside; and said housing providing a receptacle to confine plugs displaced from said perforations.
4. In an illuminated sign, a light controlling wall having an area of closely related light releasing perforations distributed thereover, and light obstructing closures removably and replaceably adapted to said perforations; said closures retaining their positions in said perforations by fitting therein when in place and being of no greater transverse dimension than said perforations at any portion of their length so that they are adapted to be passed entirely through the perforations when displaced therefrom.
5. In an illuminated sign, a light controlling wall having an area of closely related light releasing perforations distributed
- thereover, and light obstructing closures removably and replaceably adapted to said perforations; said closures retaining their positions in said perforations by fitting therein when in place and being of no greater transverse dimension than said perforations at any portion of their length so that they are adapted to be passed entirely through the perforations when displaced therefrom; the ends of the closures being flush with the surface of the wall when the closures are in place therein.
6. In an illuminated sign, a light controlling wall having an area of closely related perforations and closures for said perforations, comprising diametrically resilient plugs adapted to fit perforations and to be passed entirely through the same.
7. In an illuminated sign, a light controlling wall constructed with an area of closely related perforations and closures for said perforations, comprising hollow metallic plugs having longitudinally slit walls.
8. In an illuminated sign, a light controlling plate constructed with light emitting perforations and closures for said perforations, consisting of plugs adapted to fit the perforations and retain their positions therein; said plugs being hollow and being adapted to receive and confine the displacing instrument while they are being displaced from the wall.

Signed at Chicago, Illinois, this 21st day of February, 1922.

LOUIS A. GRAHAM.
